US00D785613S

(12) **United States Design Patent** (10) **Patent No.:** **US D785,613 S**
(45) **Date of Patent:** **** May 2, 2017**

(54) **CASE FOR A PORTABLE ELECTRONIC DEVICE**

(71) Applicant: **HTC Corporation**, Taoyuan County (TW)

(72) Inventors: **Yen-Hung Lin**, Taoyuan County (TW);
Michael Ross Massucco, San Francisco, CA (US)

(73) Assignee: **HTC Corporation**, Taoyuan (TW)

(**) Term: **14 Years**

(21) Appl. No.: **29/480,712**

(22) Filed: **Jan. 29, 2014**

(51) **LOC (10) Cl.** **14-03**

(52) **U.S. Cl.**

USPC **D14/250**

(58) **Field of Classification Search**

USPC D14/250-253, 440, 203.3-203.7, 217, D14/496, 248, 238.1, 240, 447, 230, 247, D14/341, 345, 346, 439; D3/201, 218, D3/269, 301, 273, 303; D13/103, D13/107-108; 220/4.02; 248/309.1; 361/679.56; 379/426, 433.11, 455; 455/575.1, 575.8; 190/100; 206/305, 206/320

CPC . A45C 2011/002; A45C 11/00; A45C 13/002; A45C 2011/003; H04M 1/0283; H04M 1/0202; H04M 1/185; H04B 1/3888

See application file for complete search history.

(57) **CLAIM**

The ornamental design for a case for a portable electronic device, as shown and described.

DESCRIPTION

FIG. 1 is a perspective view of a case for a portable electronic device showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line portions of the case for a portable electronic device in FIGS. 2-3, and 5-6 represent unclaimed portions of the design and form no part thereof.

1 Claim, 5 Drawing Sheets
